UNITED STATES PATENT OFFICE.

CALVIN ADKINS, OF ANSELMO, NEBRASKA.

WIRE-STRETCHER.

SPECIFICATION forming part of Letters Patent No. 764,408, dated July 5, 1904.

Application filed January 9, 1904. Serial No. 188,816. (No model.)

To all whom it may concern:

Be it known that I, CALVIN ADKINS, a citizen of the United States, and a resident of Anselmo, in the county of Custer and State of Nebraska, 5 have invented a new and useful Improvement in Wire-Stretchers, of which the following is a specification.

My invention relates to an improvement in wire-stretchers, the object being to provide a 10 simple device of powerful leverage for stretching two wires at a time or practically at the same time; and the invention consists in a frame adapted to be fastened at one end to a suitable support in connection with two 15 ratchet-toothed bars to which the wires are connected in any approved manner, a lever pivoted to the frame and carrying dogs or pawls which operate in conjunction with the toothed bars to alternately apply pressure to 20 one and then the other, and means for locking these bars against outward movement.

My invention further consists in certain 25 novel features of construction and combinations of parts, which will be hereinafter described, and pointed out in the claims.

In the accompanying drawings, Figure 1 is a view in side elevation of my improved wire-stretcher on an enlarged scale, and Fig. 2 is a view showing the wire-stretcher applied in the 30 operation of stretching two wires.

A represents the frame, which may be of any approved construction in the general dimensions—say thirty inches wide by thirty-six inches long—and it consists of the longitudinal 35 strips 1, 2, and 3 and the uprights 4 4 and 5 5 at the ends thereof. At the rear ends these uprights are provided with holes adapted to receive a ring or chain-link 6, and chains 7 7 extend rearward to a ring 8, to which another 40 chain, 9, is secured for fastening the device to a post or other support. A pair of stretching-bars 10 10 are mounted slidably in the frame just over the upper and lower longitudinal bars and between the uprights. These 45 stretching-bars have chains or similar devices 11 11 connected to their forward ends, and the grips or grabs 12 12 on their ends are provided for attachment to the wires to be stretched. These stretching-bars have ratchet-shaped teeth 13 13 on their upper edges. A

hand-lever 14 is pivoted to the central longitudinal bar, as at 15, and this hand-lever carries the pawls or dogs 16 16, which may be gravity pawls or dogs or spring-actuated, as preferred, they being in position and adapted to engage 55 the teeth of the stretching-bars. Dogs 17 17, pivoted to the frame, are arranged in position to engage the teeth of the stretching-bars, whereby to lock the bars as they are drawn forward by the hand-lever. 60

In the operation of the wire-stretcher in practice it is fastened as explained above and the grips are attached to two wires to be stretched. The hand-lever is then moved back and forth, the dogs on the frame holding the 65 stretching-bars as they are drawn forward and the pawls or dogs on the lever automatically engaging the teeth and first drawing one bar forward with the vibration of the lever in one direction and the other bar forward with the 70 vibration of the hand-lever in the other direction. In this way each motion of the lever is effectual in stretching a wire, and a motion back and forth stretches two of the wires uniformly. 75

It is evident that slight changes might be made in the form and arrangement of the several parts described without departing from the spirit and scope of my invention, and hence I do not wish to limit myself to the exact construction herein set forth; but, 80

Having fully described my invention, what I claim as new, and desire to secure by Letters Patent, is—

1. A wire-stretcher comprising a frame, 85 slidable stretching-bars having teeth thereon, means for connecting each bar to a wire, and means for locking these stretching-bars, and a lever which alternately slides the bars forward, one with each stroke of the lever. 90

2. In a wire-stretcher, the combination with a frame composed of longitudinal and upright bars, toothed stretching-bars having sliding connection with the frame, and means for connecting each bar to a wire, of a lever pivoted at a point between the stretching-bars and provided with dogs or pawls for engaging the teeth of the stretching-bars, and alternately sliding said bars forward, and means for locking the bars in their adjusted positions. 95 100

3. The combination with a frame, and a lever pivoted thereto, of two stretching-bars, means for connecting each bar to a wire and means for alternately causing the lever to engage and move first one bar and then the other endwise to stretch the wire attached thereto.
4. The combination with a frame, and a lever pivoted thereto, of two stretching-bars, means for connecting each bar to a wire and means for alternately causing the lever to en-

gage and move the bars endwise to stretch the wire attached thereto, and means for locking the bars while the lever is taking a new hold.

In testimony whereof I have signed this specification in the presence of two subscribing witnesses.

CALVIN ADKINS.
